CLAIM

The ornamental design for a toy laser gun with target assembly, as shown and described.

DESCRIPTION

FIG. 1 is a first perspective view of a toy laser gun with target assembly showing my new design with the target element removed for clarity;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a first perspective view of a second element a toy laser gun with target assembly showing my new design with the gun element removed for clarity;

FIG. 10 is a second perspective view thereof;

FIG. 11 is a front view thereof;

FIG. 12 is a back view thereof;

FIG. 13 is a left side view thereof;

FIG. 14 is a right side view thereof;

FIG. 15 is a top view thereof;

FIG. 16 is a bottom view thereof; and,

FIG. 17 is a perspective view of the toy laser gun with target assembly shown with the gun and target elements together. The broken lines shown in the drawings depict portions of the toy laser gun with target assembly that form no part of the claimed design.
